TOWEL HOLDER

Herbert D. Lawson, Washington, D. C., assignor
to Mason Can Company, East Providence,
R. I.

Application June 10, 1935, Serial No. 25,934

3 Claims. (Cl. 242—55.2)

This invention relates to a towel holder and is designed primarily for supporting rolls of paper towels so that they can be held under a slight restraint and thus be prevented from turning too freely when the paper is pulled.

A further object is to provide a device of this character which can be made at low cost, and which, when not in use, can be easily folded so as to facilitate packing and storage.

10 A still further object is to provide a towel holder formed of few parts and which will not readily get out of order.

15 With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention 20 as claimed.

In the accompanying drawing the preferred form of the invention has been shown.

In said drawing

25 Figure 1 is a plan view of the towel holder in open or operative position.

Figure 2 is a section on line 2—2 Figure 1.

Figure 3 is a section on line 3—3 Figure 2.

30 Figure 4 is an end elevation showing the spring pressed arm folded.

Referring to the figures by characters of reference, 1 designates an attached plate of any desired proportions adapted to be fastened in any suitable manner to a wall or other supporting structure and this base plate has a pair of ears 2 struck therefrom adjacent to each end.

35 Each pair of ears is straddled by opposed flanges 3 of a side arm 4 formed preferably of sheet metal and the outer or free end portion of each arm carries a knob-like bearing element 5.

40 As before stated the flanges 3 are pivotally joined to the ears 2. Therefore the adjacent end or edge 6 of each arm 4 constitutes a means for moving against plate 1 to limit the swinging movement of the arm 4 in one direction relative to the plate 1. Movement of each arm in the opposite direction is unrestrained until the bearing element 5 comes against the plate. Thus 45 the structure can be folded as indicated by pack-dotted lines in Figure 1 for convenience in packing and storing.

45 In order that one of the arms may exert a constant thrust toward the other arm when 50 opened outwardly to its extreme full line position

5 tion in Figure 1, a short spring blade 7 is inserted through a transverse slit 8 in the base plate 1. Thus one end of this blade will be supported in contact with the back surface of plate 1 where it can be secured by a rivet 9 or the like. 5 The other end of the blade will extend between the ears 2 and across the end of arm 4. If desired a narrow bearing flange 10 can be provided along this end of arm 4 for the purpose of engaging the spring 7 and placing it under tension by forcing 10 it back toward plate 1 when said arm 4 is opened outwardly as in Figures 1, 2 and 3.

When it is desired to use this rack the two arms are opened as in Figure 1 so as to place spring 7 under maximum tension and to provide a sufficient clearance between the bearing elements 5 to permit the insertion of a roll of paper between the arms. These rolls are generally formed with tubular cores. Thus when the arms are released following the insertion of a roll, the spring pressed 20 arm 4 will move automatically against the end of the roll so that said roll will thus be clamped between the two arms and the bearing elements 5 held within the ends of the roll.

Consequently when a length of paper is pulled 25 from the roll said roll will turn readily because the pressure exerted by the spring pressed arm 4 is not excessive. Such pressure however is sufficient to prevent the roll from spinning.

It will be noted that the structure is very simple in construction and all of the parts can be easily produced with dies whereby the parts can be struck from sheet metal. The number of parts is reduced to the minimum and because of its simple construction the device will not 30 readily get out of order.

35 What is claimed is:

1. A towel holder including a base plate having spaced pairs of ears extending therefrom and a slot adjacent the ears of one pair, opposed arms 40 hingedly connected to the respective pairs of ears, and a leaf spring or blade extending through the slot and fastened at one end to the plate while its other or active end is extended freely between the adjacent ears and across one end of the adjacent arm between said arm and the base, said spring constituting means for normally pressing said arm yieldingly toward the opposed arm.

2. A towel holder including a base plate having spaced pairs of ears extending therefrom 50 and a slot adjacent the ears of one pair, opposed arms hingedly connected to the respective pairs of ears, and a leaf spring or blade extending through the slot and fastened at one end to the plate while its other end is extended freely 55

between the adjacent ears and across one end of the adjacent arm between said arm and the base, said spring constituting means for normally pressing said arm yieldingly toward the opposed arm, and a bearing element on said arm for exerting a thrust against the spring to place it under compression when the arm is moved out of normal position in either direction and for holding the arm folded toward the base when the arm is forcibly shifted in one direction away from normal position.

3. A towel holder comprising a base plate formed of sheet metal having opposed pairs of ears struck therefrom and a slot adjacent the ears of one pair, opposed arms each formed of sheet metal and having opposed flanges, the flanges of said arms being hingedly connected to

the ears of the respective pairs and each arm having one end movable against the plate to limit the swinging movement of the arm in one direction relative to the base plate, a spring blade extending through the slot in the base and having one end back of and secured to the base plate and its other end free and extended between the base and the arm, said free end of the spring being in yielding contact with the end of the adjacent arm, a flange on the arm engaging the spring thereby to hold said spring under tension when said arm is moved in either direction out of normal position, said flange and spring cooperating to hold the arm yieldingly pressed toward the base when the arm is forcibly moved out of normal position into folded position onto the base. 5 10 15
